US0D1041132S

(12) **United States Design Patent** (10) Patent No.: **US D1,041,132 S**
(45) Date of Patent: ** Sep. 10, 2024

(54) **SNEAKER**

(71) Applicant: **BOTTEGA VENETA S.R.L.**,
Montebello Vicentino (IT)
(72) Inventor: **Matthieu Blazy**, Milan (IT)
(73) Assignee: **Bottega Veneta S.R.L.**, Montebello
Vicentino (IT)

(**) Term: **15 Years**

(21) Appl. No.: **35/519,469**

(22) Filed: **Dec. 6, 2023**

(80) **Hague Agreement Data**

Int. Filing Date: **Dec. 6, 2023**

Int. Reg. No.: **DM/233808**

Int. Reg. Date: **Dec. 6, 2023**

Int. Reg. Pub. Date: **Dec. 22, 2023**

(30) **Foreign Application Priority Data**

Jul. 19, 2023 (EM) 015028555-0003

(51) **LOC (14) Cl.** **02-04**
(52) **U.S. Cl.**
